UNITED STATES PATENT OFFICE.

ELBRIDGE R. HOLMES AND ALLAN S. HUTCHINS, OF WORCESTER, MASSACHUSETTS,
ASSIGNORS TO CROMPTON & KNOWLES LOOM WORKS, OF WORCESTER, MASSACHUSETTS,
A CORPORATION OF MASSACHUSETTS.

WARP LET-OFF FOR NARROW-WARE LOOMS.

Application filed April 29, 1922. Serial No. 557,385.

To all whom it may concern:

Be it known that we, ELBRIDGE R. HOLMES and ALLAN S. HUTCHINS, both citizens of the United States, residing at Worcester, in 5 the county of Worcester and State of Massachusetts, have invented a new and useful Warp Let-Off for Narrow-Ware Looms, of which the following is a specification.

This invention relates to a let-off particularly designed for use in connection with narrow ware looms in which the warp for a particular fabric is distributed on several warp beams or spools. In order to produce a uniform and satisfactory fabric, the tension upon all parts of the warp should be kept as nearly uniform as possible. For this purpose, it is customary to loop the warp threads around weighted pulleys which have a considerable range of vertical 15 movement while applying constant tension to the warp. It is necessary, however, that fresh warp be let off from the spools at frequent intervals and it is the object of our invention to provide improved mechanism 20 under the control of the tension pulleys by which the warp spools may be intermittently released to deliver warp to the tension pulleys.

In the preferred form of our invention, 30 the rotation of the spools is retarded by engagement of a friction plate on each spool by a pair of friction pads pressed against the opposite faces of the plate.

An important feature of our invention relates to improved means for reducing or 35 relieving the friction on the plate whenever rotation of the warp spool is desired. A further feature relates to the provision of an improved construction by which removal 40 of the warp spools is facilitated.

Our invention further relates to arrangements and combinations of parts which will be hereinafter described and more particularly pointed out in the appended claims.

45 A preferred form of our invention is shown in the drawings in which

Fig. 1 is a side elevation of a portion of a loom having our improved let-off applied thereto;

50 Fig. 2 is an enlarged front elevation of a portion of one of the warp spools and its friction device;

Fig. 3 is an enlarged side elevation of the parts shown in Fig. 2;

Fig. 4 is a detail sectional view, taken 55 along the line 4—4 in Fig. 2;

Fig. 5 is a detail sectional elevation, taken along the line 5—5 in Fig. 3;

Figs. 6 and 7 are side and front elevations of the friction lever support, to be 60 described;

Fig. 8 is a detail sectional view, taken along the line 8—8 in Fig. 1, and

Fig. 9 is a detail rear elevation, looking in the direction of the arrow 9 in Fig. 1. 65

Referring to the drawings, we have shown a loom side 10 having a warp frame 11 mounted vertically thereon. A plurality of warp beams or spools 12 are loosely mounted on studs or pins 13 fixed in bars 14 pivoted 70 at 15 to brackets 16 secured to the warp frame 11. At its lower end, each bar 14 is forked as indicated in Fig. 9 to receive a clamping bolt 17 (Fig. 1). By loosening the bolt 17 and allowing the bolt to swing 75 downward, any bar 14 may be swung rearward to bring the spools 12 on that particular bar out of alignment with the remaining spools, thus permitting convenient removal and replacement thereof. 80

The warp threads W on the spool 12 are passed over rear guide pulleys 18 and are then passed over a series of additional guide pulleys 19. Each group or section of warp threads from a spool 12 is permitted to hang 85 downward and form a loop between adjacent rolls 19, and a tension pulley 20 is supported by each looped section of warp threads.

The pulleys 20 are provided with elongated depending frames 21 supporting weighted hangers 22 at their lower ends. A suitable number of weights 23 will be placed on each hanger to give the desired tension to a particular section of warp threads. 90

After leaving the guide pulleys 19, the warp threads W may be brought downward around additional guide pulleys 24 (Fig. 1) from which point they extend forward to the lay and reed. 100

The spools 12 may be of any desired construction and are herein shown as each having a steel barrel 25 (Fig. 5) and disc-like steel heads 26. An opening 27 is formed in one of the heads 26 and is positioned to receive a headed stud 28 fixed in a friction disc 29 rotatably mounted on the pin or stud 13. 105

The opening 27 is large enough to admit the head of the stud 28 and the pull of the warp on the spool moves the stud to the relative forward position shown in dotted lines in Fig. 3, in which position the head of the stud prevents axial displacement of the spool. When the spool is to be removed, however, it may be easily turned backward sufficiently to center the head with the opening, permitting withdrawal thereof.

Each disc 29 is positioned between a pair of friction pads 30 and 31. The pad 30 is mounted on a bracket 32 (Fig. 2) fixed to the bar 14. The pad 31 is preferably formed in the shape of a ring as shown in Fig. 4, and is secured to the face of a lever 33 pivotally mounted on a stud or support 34 adjustably secured in the bar 14 by a set-screw 35. The lever 33 extends forward from its pivot and projects into the loop or frame 21 of the corresponding tension pulley 20.

The support or stud 34 has a cylindrical shank engaged by the set screw 35 and a bearing portion or head provided with multiple screw threads 36 of very steep pitch, sextuple threads being shown in the drawings. The lever or arm 33 is threaded to fit the threads 36 and the stud 34 is provided with a screw-driver slot 37 by which it may be angularly adjusted.

Having described the construction of our improved let-off, the operation thereof is as follows: As the fabric is woven, each tension pulley 20 is gradually raised until the lower end of its loop frame 21 engages the corresponding lever 33. Up to this point, the lever 33, assisted if desired by a supplementary weight 38, has supplied sufficient friction to the disc 29 to prevent rotation of the spool. As soon, however, as the lever 33 is engaged and moved upward by its tension pulley, its threaded support 34 has a cam action on the lever to withdraw it slightly axially and thus reduce or release the friction on the disc 29. The remaining friction of the pad 30 is merely sufficient to prevent free or idle rotation of the spool.

The spool thus released lets off a certain amount of warp, permitting the corresponding tension pulley 20 to descend. This movement frees the arm 30 and the friction on the disc 29 is thus restored.

As it is found that a comparatively light weight on the lever 33 is sufficient to hold the spool 12, the lifting of the lever by the tension roll 20 does not materially increase the tension on the warp threads by which the roll is supported.

It is thus possible to gradually let off the warp from each warp spool 12 independently of all of the other spools, at the same time maintaining substantially uniform tension thereon. This permits the different spools to be used on different portions of the fabric in which different amounts of

warp may be consumed and in which different warp tensions may be desired.

Particular attention is called to the extreme compactness of the design, as indicated in Fig. 2. This is of material importance as the available space between adjacent sets of warp spools is very limited.

While shown and described as applied to a narrow ware loom, certain features of our invention are also applicable to other types of looms, such as broad looms in which a fancy selvage is to be woven at the edge of the fabric.

Having thus described our invention and the advantages thereof, it will be evident that changes and modifications can be made therein by those skilled in the art within the spirit and scope of our invention as set forth in the claims, and we do not wish to be otherwise limited to the details herein disclosed, but what we claim is:—

1. In a narrow ware loom, a warp holder, means to frictionally resist rotation thereof, and means to intermittently release said holder, said friction means including an angularly movable friction member, a fixed support for said member, said member and support having co-operating cam surfaces, and warp controlled means to move said friction member angularly on its support, whereby the cam surfaces of said support act effectively and directly on said friction member to withdraw said member from operative holding position relative to said warp holder in a direction substantially perpendicular to the plane of angular movement of said friction member.

2. In a narrow ware loom, a warp holder, means to frictionally resist rotation thereof, and means to intermittently release said holder, said friction means including an angularly movable friction member, a fixed support for said member, said member and support having co-operating multiple threads, and warp controlled means to move said friction member angularly on said fixed support thereby changing its axial position thereon in a direction substantially perpendicular to the plane of angular movement of said friction member and decreasing the frictional resistance of said friction member against rotation of said warp holder.

3. In a narrow ware loom, a warp holder, means to frictionally resist rotation thereof, said friction means including a fixed friction member, a disc rotatable with said warp holder and adjacent said fixed member on one side, and a movable friction member effective to engage the opposite side of said disc and to press the disc against said fixed friction member, and warp controlled means to intermittently withdraw said movable friction member to release the drag on said disc and warp holder,

4. In a narrow ware loom, a plurality of headed warp spools, and a plurality of vertically extended supporting bars on which said spools are rotatably mounted, said bars being pivoted to swing rearwardly about the upper ends thereof and substantially in the plane of the spool heads and being de-

tachably secured to the loom at their free lower ends.

In testimony whereof we have hereunto affixed our signatures.

ELBRIDGE R. HOLMES.
ALLAN S. HUTCHINS.
